UNITED STATES PATENT OFFICE.

OSCAR A. SKOGEN, OF LA CROSSE, WISCONSIN.

DESIGN FOR A PUZZLE.

Application filed July 14, 1924. Serial No. 10,151. Term of patent 7 years.

To all whom it may concern:

Be it known that I, OSCAR A. SKOGEN, a citizen of the United States of America, residing at La Crosse, in the county of La Crosse and State of Wisconsin, have invented a new, original, and ornamental Design for a Puzzle, of which the following is a specification, reference being had to the accompanying drawing, forming a part hereof.

The drawing is a perspective view of a puzzle showing my new design.

I claim:

The ornamental design for a puzzle, as shown.

OSCAR A. SKOGEN. [L.S.]
